UNITED STATES PATENT OFFICE.

DAVID JOSEPH MARX, OF CHICAGO, ILLINOIS.

CAR-COUPING.

SPECIFICATION forming part of Letters Patent No. 435,072, dated August 26, 1890.

Application filed February 12, 1890. Serial No. 340,234. (No model.)

To all whom it may concern:

Be it known that I, DAVID JOSEPH MARX, of Chicago, Cook county, Illinois, have invented a new and Improved Automatic Coupling, of which the following is a full, clear, and exact description.

My invention relates to that class of car-couplers having a pivotal swinging pin for use with an ordinary link; and an object of my invention is to provide means for lifting and lowering the said pin.

My invention further relates to the improvement of a car-coupler which shall provide an automatic means of both coupling and uncoupling ordinary link couplers without the use of springs, ropes, cables, pulleys, and chains, which are easy to get out of order.

Another object of my invention is to provide a crank-arm coupler and uncoupler free to give with the draw-bar springs, there being no part attached to the body or wood-work of the car; to provide a coupler requiring less exertion to operate than in lever-couplings now in use, and to provide a cheap, neat, and secure device well adapted for use on all classes of cars. I attain these objects by the mechanism illustrated in the annexed drawings.

Like figures and letters denote like parts in the separate figures.

Figure 1 shows a perspective side view of opposing draw-heads in position for coupling, having my improved device attached. Fig. 2 shows a longitudinal side view of the same. Fig. 3 shows a broken front, top, and inside view showing the link engaged or coupled. Fig. 4 shows a sectional view showing modifications explained hereinafter.

The draw-head A is provided with the flaring mouth common to ordinary link couplers. Situated on the floor of the inside of the draw-head d is the shoulder or flange D, the top surface of which is arched or hollowed out at D' to accommodate the crank-bar I, bent in the shape of a double crank D C. This, the link-lifting device, is suspended from its axes H, so as to embed itself in the cavity D', so as to escape and pass under the link G as it passes inward. The crank-bar I is provided with handles J within easy reach from the sides of the car.

Protruding from the crank-bar I are two fin-

gers or cams K, one on each side of the outside of the draw-head. When handles J are turned upward, they bring these cams in position to bear against the sides P of a lifting device or frame F. This frame is swiveled to the flange of draw-head L by means of the bolts or pivots M, and the sides P are mortise-joined to the front Q, and of which the outer ends are threaded for the reception of nuts O, which may be riveted and made fast. Suspended from the center of the front of the frame F is the pin B, which is free to swing on its pivotal axis in the perforation in the head of the pin. Provided in the top of the draw-head is the peculiar-shaped slot C. Passing through this slot is the pin B, so as to bear against the forward edge of the said slot at the top, and the flange or shoulder D, provided at the bottom, and both bearings being cut away at an angle facilitates the hanging of the pin at an angle when engaging the link G and when at rest, which adds strength. When the cams K are brought to bear against the sides P of the lifting-frame F, and force it and the pin suspended thereto upward to a sufficient height to draw the pin from out the link, they are checked from further progress by the brakes N.

From the foregoing it will be seen that the operation of my improved car-coupler is as follows: The entering link G strikes against the front surface of the pin B, forcing it backward and upward until the link passes inward, when gravitation sends the pin forward and downward through the link and resting the said pin against its angular bearings, before described, thus securely coupling said link automatically. When the cams K are brought to bear against the sides P of the frame F, by turning handles J upward it draws the pin B upward through slot C and from out link G, releasing said link automatically. When the handles J are reversed downward, they allow the pin to drop into its normal position to couple. Should it be desired to couple two cars the draw-heads of which are of unequal height, the operator turns the crank-handle j of lower draw-head forward, (the double crank D C being underneath the link G in its cavity D',) raising the said link to the flaring mouth of the opposite draw-head.

In Fig. 4, showing a modified view, the link-lifting device consisting of the double crank D C, instead of being joined to the crank-arms as one piece, is separated and swiveled to the sides of the draw-head by means of the bolts *m'*. The crank arms or bar I passes through the draw-bar in a straight line, instead of being bent, and carrying the outside cams *k* and the inside hooks or cams K O, which bear against the double crank D C.

Having thus fully described my invention, I claim as new and desire to secure by Letters Patent—

1. The combination, in a car-coupler, of the draw-head A, provided with the peculiar angular-shaped slot C, the angled flange D, the arch-shaped cavity D', the crank bar or arms I, bent into the double crank D C, resting on the axes H, having the handles J, the cams K, and the brakes N, substantially as and for the purpose described.

2. The combination, in a car-coupler, of the draw-head A, provided with the rear flange L, the U-shaped pin or lug lifting frame F, swiveled to the flange L by means of the bolts M, the pin or lug B, suspended on its pivotal swinging axis by the perforation in its head E from the center of the frame F, and the link G, substantially as and for the purpose described.

3. In a car-coupler, the combination of a draw-head having a pin-opening through the top and a flange or stop on the bottom coinciding with the front of the pin-opening, a pin and a swinging frame or bar to which said pin is attached, a crank for operating the link, and a cam for operating the pin frame or bar, as set forth.

4. In a car-coupler, the combination of a draw-head having an elongated and undercut or beveled pin-opening through the top, a flange or stop on the bottom, and a depression or recess in front of said flange or stop, a swinging and lifting pin and a frame or bar to which it is attached, said frame or bar being pivoted to the top of the draw-head, a crank working within the draw-head having its horizontal limb lying in the depression or recess, and a cam on shaft of said crank for operating the pin frame or bar, as set forth.

5. The combination of a draw-head having a top flange or projection on the rear thereof and provided with a pin-opening through the top and a projection or stop on the bottom, as described, a frame consisting of side bars pivoted to the top flange and a rod connecting the front of said bars, a coupling-pin swiveled on said rod, a crank for operating the link, and a cam connected to the shaft of the crank for operating the frame, as set forth.

6. The combination of a draw-head having a pin-opening through the top and a stop or flange in the bottom, a swinging and lifting pin, and a cam for raising said pin, as set forth.

7. The combination, with a draw-head having a pin-hole through the top, a stop in the bottom, and a projection or brake on the side, of a pin and a cam for raising said pin, the movement of the cam being limited by the brake, as set forth.

DAVID JOSEPH MARX.
